Primary Examiner—Wallace R. Burke*Assistant Examiner*—M. H. Tung*Attorney, Agent, or Firm*—Rogers, Howell & Haferkamp**[57] CLAIM**

The ornamental design for a trigger sprayer, as shown and described.

DESCRIPTION

FIG. 1 is a top plan view of a trigger sprayer showing my new design;

FIG. 2 is a right side elevational view thereof;

FIG. 3 is a rear elevational view thereof;

FIG. 4 is a front elevational view thereof;

FIG. 5 is a left side elevational view thereof;

FIG. 6 is a bottom plan view thereof; and,

FIG. 7 is a top perspective view thereof, the broken line drawing of the nozzle tip and neck attachment are for illustrative purposes only and form no part of the claimed design.

FIG. 1.FIG. 3.FIG. 2.FIG. 4.FIG. 6.FIG. 5.
